(57) **CLAIM**

The ornamental design for universal portable-device charger, as shown and described.

DESCRIPTION

FIG. 1 is a perspective view of a universal portable-device charger according to our new design;

FIG. 2 is a front view of the universal portable-device charger of FIG. 1;

FIG. 3 is a right side view of universal portable-device charger of FIG. 1;

FIG. 4 is a left side view of the universal portable-device charger of FIG. 1;

FIG. 5 is a top view of the universal portable-device charger of FIG. 1;

FIG. 6 is a bottom view of the universal portable-device charger of FIG. 1; and,

FIG. 7 is a rear view of the universal portable-device charger of FIG. 1;

The broken line showing of the environment is for illustrative purposes only and forms no part of the claimed design.
